UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

SERIES BOILER AND METHOD OF OPERATING THE SAME.

Original application filed April 16, 1918, Serial No. 228,827. Divided and this application filed June 19, 1920, Serial No. 390,072. Renewed February 11, 1926.

This invention relates to series boilers and methods of operating the same.

Fig. 1 is a diagrammatic sectional side elevation showing one form of my improved boiler provided with a hand-fired coal furnace and showing, also, feed water apparatus and superheat limiting apparatus; Fig. 1^a is a horizontal section taken through the tank 12 just above the float 21; Fig. 1^b is a section taken along the plane of the line 1^b—1^b of Fig. 1^a; Fig. 2 is a detail of the regulating valve controlling steam for driving the feed pump in Fig. 1; Fig. 3 is a view similar to Fig. 1, showing my improved boiler provided 15 with an underfeed stoker—this view also showing a superheat limiting device and also a device for regulating the temperature of the superheated steam; Fig. 3^a is an enlarged sectional view through the relief valve 129; Fig. 3^b is a section taken on the plane of the line 3^b—3^b of Fig. 3^a; Fig. 4 is a view similar to Fig. 1, showing a modified form 20 of the boiler with its units arranged in a different relation; Fig. 5 is a sectional side elevation of my improved boiler showing oil-firing and arranged for practical use as regards the preferred general proportions of headers and tubes, although the view is partially diagrammatic; Fig. 6 is a partial end 25 elevation of a portion of Fig. 5, showing the supporting of the header boxes.

My invention relates to forced circulation series boilers and the method of operating the same, and is designed to provide an improved boiler of this type, on which I have conducted experiments for a considerable period of time. In the preferred form of my boiler, a series of boiler header boxes is used, with tubes, preferably of U-form, extending 30 upwardly therefrom.

The present application, which is a division of my prior application Serial No. 228,827, which was filed in the Patent Office on or about April 16, 1918, relates more particularly to the feeding system including the steam and water drum, which acts as a steam separating drum or tank, and the parts associated therewith, including connections for leading steam and water thereto from the 35 series boiler, and means for feeding water from said drum, and to the method of operating a boiler of this type. Water is passed by forced circulation through tubes in series, and the feed water for the boiler is controlled 40

by the level of the water in the separating drum or tank.

In the forms of Figs. 1 to 4, inclusive, the header boxes are shown much larger and the U-tubes much shorter than I prefer to employ in practice, for clearness of illustration 50 of the principles involved.

In Fig. 1, 2 represents the header boxes and 3 the series of U-shaped tubes extending upwardly therefrom; the boxes being preferably transverse to the flow of the gases and 55 protected therefrom by the refractory bottom 4 of the furnace chamber. In this form of Fig. 1, the portion A is made up of the tubes most remote from the source of heat, which is indicated as a furnace 5 having a 60 hand-fired grate 6. B indicates tubes nearer the source of heat than the tubes A and C represents the superheater tubes, which, in this form, are nearest the source of heat, 65 being the offtake flue for the gases. The 70 hottest gases flow over the hottest heating surface and the coldest gases over the coldest surface, thereby embodying the so-called 75 counterflow principle.

The feed water enters the boiler through 80 the pipe 8 leading into the rearmost header box. This water flows thence through the U-shaped tubes and the successive boxes of the series toward the furnace end, passing as 85 water and, after steam is generated, as combined, steam and water, forwardly through the successive boxes and tubes to the header 9, which is the foremost header of the boiler tubes proper. From this header 9 the steam, 90 with a regulated amount of water, passes down through a pipe 11 into a tank 12, the pipe 11 having a hand-controlled valve 13. The pipe 11 also has a cross-over pipe, provided with a hand-controlled valve 14 and leading to a pipe 15 which conducts the steam 95 from the tank to the rear header 16 of the superheater. The pipe 15 also has a hand-controlled valve 17. From the superheater header 16 the steam flows through the U-tubes into the exit header 18, from which it 100 flows through the outlet pipe 19.

The water fed to the boiler is controlled in the following manner:

The feed pipe 8 is provided with a loop adjacent to the tank 12, this loop having a 105 valve, shown at 20, controlled by a float 21 lying on the body of water in this tank. The shaft of the float-lever extends through a

stuffing-box in the side of the tank and is connected to the valve-stem of the valve or cock 20. Should the water level fall in the tank 12, more feed water is admitted through the 5 pipe 8 into and through the series boiler, which will restore the water level in the tank. Should the water level rise in the tank, the supply of feed water will be reduced and the level will correspondingly fall in the tank 10 12. The feed water is forced into the boiler by a pump 22, to which water is supplied from the tank 23 through the pipe 24, make-up water being supplied to the tank 23 through the valved pipe 25*. The steam for 15 the feed pump enters through pipe 25, having a diaphragm-controlled valve 26, shown in detail in Fig. 2. This valve is controlled by the pressure in the water feed pipe 8, which has a branch 27 provided with a pressure gauge 28 and leading to one side of the 20 flexible diaphragm 29. The pressure on this diaphragm is resisted by a spring 30 bearing against the plate 31, which acts on the center of the diaphragm. The spring 30 surrounds 25 the stem of the control valve 26 for the steam inlet pipe 25. By making the spring of proper strength, the valve may be arranged to close at the pressure desired on the exit side of the feed pump, which pressure is 30 transmitted to the side of the diaphragm opposite the spring. The diaphragm-controlled valve will, therefore, remain fully open until the pressure in the pipe 27 reaches a predetermined point, when the spring will be 35 compressed and the valve will begin to close, thus reducing the speed of the feed pump, after which the valve will be adjusted to a position which will keep the pressure on the exit side of the pump within the desired 40 range.

Instead of the diaphragm-controlled valve shown in Fig. 2, any well known device for controlling the speed of a feed pump may be employed to maintain a reasonable uniform 45 pressure of discharge on the water from the pump. I may use a diaphragm-controlled valve so arranged that the pressure of the water being pumped can be varied at will by adjusting the valve, such a valve being an 50 ordinary commercial product.

The final header 9 of the boiler is preferably provided with a safety valve, shown in Fig. 1 at 33, and the outlet pipe 19 from the superheater 18 is preferably provided with 55 a branch 34 having a safety valve 35 and a stop valve 36. The stop valve is used in starting up the boiler and to maintain a circulation through the boiler in case of a sudden shut-down.

60 I have also shown, in Fig. 1, a superheat limiting apparatus. In this form, the steam from the pipe 19 flows through a pressure regulating valve 37 and a stop valve 38, which is wide open under normal conditions, and thence down through the chamber 39 over

the coil 40 of a superheat limiting device, and thence to supply pipe 41, which passes to any desired apparatus.

The pressure generated in the coil 40 acts upon the superheat limiting device, generally indicated at D, and which is fully described in my Patent No. 1,328,997, which was issued on or about January 27, 1920.

In Fig. 1 this device acts by admitting cold air to the interior of the boiler setting in case 75 the superheat exceeds a certain predetermined figure. This air is admitted through the doors 42, which in the figure are indicated as open—the arrows showing the inflow of air therethrough.

The superheat limiting device acts only in case of excessive superheat, the amount of superheat being normally such that the doors 42 are closed and no air is admitted through these door openings into the setting. The 80 surface of the superheater C is so formed that the superheat will be normally below a figure which will give trouble. In case of a sudden shut-down, or any other irregularity in operation which would lead to excessive 85 superheat, the superheat limiting device D is brought into action in the same way as the safety valve on a steam boiler is called into action when the steam pressure exceeds that for which the safety valve is set. The superheat limiting device herein shown is a safety device for preventing excess superheat and is not a device for regulating the amount of 90 superheat.

In starting up such a series boiler from a 100 cold condition, all parts of the boiler, including the superheater, are filled with water under pressure. The air within the boiler need not be removed, but by feeding in water at a high pressure the volume of air 105 pocketed in the boiler is comparatively small. Some water is preferably allowed to flow through the boiler before starting to remove a portion of the air which would otherwise be pocketed, this water being allowed to 110 escape through the stop valve 36.

At this time, when the apparatus is flooded with water preparatory to starting, the valves 13 and 17 are closed and the valve 14 is open. After steam is formed, steam and water are 115 allowed to escape through the valve 36. When the flow of steam and water through the valve 36 becomes reasonably uniform, the valves 13 and 17 are slowly opened and the valve 14 closed. The water fed during the period of starting up is regulated by means of the feed valve 128. In starting up, the water is maintained at such a level in the tank 12 that the valve 20 which is controlled by the float 21 remains open, the water level being indicated by a water glass, indicated at 43. After starting up the feed pump is governed to maintain a given height of water in the tank 12, which will cause the amount of water flowing into the tank through the 120 125 130

- pipe 11 to be governed by the amount of water which is allowed to flow from the bottom of the tank through a pipe fitted with the throttle valve 45 and into the feed tank 23. By adjusting the throttle valve 45, the water may be blown from the tank 12 at any desired rate and with the water in the tank 12 maintained at a constant level, the water in the steam, which enters the tank 12, will enter the tank at the same rate as the water is blown away from the tank 12. The tank 12 is fitted with a blow-off connection 44 to remove any sediment accumulating in the tank and to drain the tank 12.
- It will thus be apparent that my series boiler operates on a closed circuit, the water, which is withdrawn from the separating tank 12 at a predetermined constant rate, which is regulated by the valve 45, passing into a reserve tank 23, to which the make-up water is supplied. The reserve tank 23 thus constitutes a source of water supplementing the amount that is withdrawn from the tank 12 and the amount that is fed to the boiler.
- In operating the boiler, the pressure is kept within the desired range in the feed pipe, the pressure being indicated by the pressure gauge 28. The frictional resistance of the water and steam flowing through the series boiler is a material factor, and the pressure of the feed water entering through the pipe 8 must be sufficiently high to overcome the frictional resistance of the flow. This frictional resistance varies greatly, increasing with the load, and the pressure of the feed water entering through the pipe 8 may be varied in accordance with the conditions under which the boiler may be operating. The steam and water from the box 9 enters the tank 12 where the two separate, and the steam passes up through the valve 17 to the header box 16 of the superheater and thence through the superheater limiting system to the point of offtake.
- In Fig. 3 I show a form similar to that of Fig. 1, the similar parts being marked with the same numerals with the letter "a" applied, the underfeed stoker 46 being employed.
- In this figure I also show the coil 40^a of the superheat limiting device as placed in the outlet pipe 19^a of the superheater. In this figure I also show an additional feature, consisting of the superheated steam attemperating device marked 47, which acts to regulate the temperature of the superheated steam discharged from the superheater. This attemperating device is similar to one shown in my Patent No. 1,149,265, dated August 10, 1915, for method of and apparatus for regulating the temperature of superheated steam.
- The attemperator admits a regulated amount of water in the superheater through the valve 48 and smaller pipe connections 49, which enter the superheater header box 16^a at various points in its length. The water admitted to the superheater is obtained from the tank 12^a through the pipe 50, the pressure in the tank 12^a being maintained somewhat higher than that in the superheater by throttling the steam leaving the tank by means of the valve 17^a. The difference in pressure between the tank 12^a and the superheater is indicated by the readings of the pressure gauges 51 and 52. The attemperator 47 regulates the amount of water supplied through the pipe 50 by opening and closing a stop cock 53, being governed through the temperature of the superheated steam surrounding the coil 40^a. The superheat limiting device D^a is not brought into action except when through some unusual circumstance the superheat becomes higher than it should be, in which case cold air is admitted to the setting as before and the damper 54 is closed, this damper admitting forced blast to the stoker.
- In this form, a float valve 55 of any well known form is attached to the outlet of the pipe 25^a to regulate the amount of water supplied to the feed tank. I also show three sets of superheater tubes, the intake ends of the tubes being extended down near the bottoms of the headers, shown at 56, to reduce the amount of water that would tend to pocket in the superheater headers.
- In this figure I show a diaphragm controlled-valve 26^a attached by the pipe 27^a to the discharge pipe leading from the feed pump. The function of the diaphragm controlled-valve 26^a is the same as that of the valve 26 in Fig. 1. A relief valve 129 is placed on the discharge side of the feed pump and in case of the closure of the float-operated valve 20^a, resulting in an over-pressure, it by-passes some of the water back to the feed tank 23^a. The speed of the pump may be regulated by hand in starting up the boiler by adjusting the throttle and stop valve G in the steam pipe leading to the pump.
- In Fig. 4 I show a form in which the boiler portion of the tubes B^a is divided into two parts, one part acted upon by the hottest gases and the other by the gases after they have passed the superheater portion C^a.
- In this figure the separator tank 12^a is shown as a horizontal cylinder or drum, and the amount of feed water admitted to the boiler through the pipe 8^a is regulated by a feed regulating device 64 of well known construction, so as to maintain an approximately constant level of water in the tank 12^a. The water from the tank 12^a in this form passes through the valved pipe 45^a to the feed tank 23^a, a coil 65 being used to transmit the heat from the water passing from the tank 12^a into the feed tank 23^a and prevent loss of heat through the vapor escaping from the point 130.

where the hot water from the valved pipe 45^d mixes with the water in the tank.

Fig. 4 is incomplete in certain essential features, to bring out more clearly the special features illustrated therein.

In Fig. 5 I show a series boiler arranged to be heated by an oil furnace, and of a general form which experiments have indicated as preferable, as regards the general proportions of the tubes and headers. The parts are marked with numerals in accordance with the previous figures, with the letter "e" applied, the boiler portion being divided into two sections B^e with the superheater C^e between them; so that the hot gases from the furnace contact with a portion of the boiler or evaporating tubes, thence over the superheater tubes, thence over further boiler tubes, and thence over the economizer tubes 20 A^e, before reaching the uptake 7^e. The oil burners 66 may be spaced along the front of the furnace, a part of which is broken away in the drawing.

In this form, the feed water in the pipe 25 8^e enters the rear header box 2^e, and thence flows upwardly through the tubes 3^e, and thence downwardly to the header box 67. From this header box the water then flows upwardly through tubes 68 into the header 30 69. The headers 69 are at a slightly higher level than the headers 67, and the tubes 68 are spaced alternately with reference to the downtake tubes leading into the header box 67. The succeeding arrangement is similar, 35 the down-flow tubes being spaced alternately with the up-flow tubes of each box until the header 70 is reached. From this header the steam and water flows through tubes 71 which have wider bends bridging the superheater 40 tubes and entering the header 72. From the header 72 the steam and water flows progressively through the boiler tubes and finally enter the header 9^e. From this header the steam and water pass through a series of pipe 45 connections 73 into a cross-pipe 74. The water is separated from the steam in this cross-pipe, and the water flows through one or more small pipe connections 75 (only one being shown) through the valved connection 50 76 and to the tank 12^e. From the separating pipe 74 the steam, from which the greater part of the water has been separated, passes upwardly through the small pipes 77 into the superheater header 78. From this header 55 the steam passes through the superheater tubes into the superheater header 74', from which it is taken away. The water is maintained at an approximately constant level in the tank 12^e by any of the means thus far described, a certain amount of water being allowed to continuously escape through the throttle valve 45^e, for the purpose previously set forth.

The preferred method of supporting the 60 tubes in the headers is illustrated in Fig. 6,

which also shows the arrangement of the down-flow and up-flow tubes for the headers. As shown, the support consists of cast iron pieces 79 held in place by bolts 80 and secured, in turn, by the beams 81. The supporting pieces 79 may interfere with the removal of the fittings opposite the ends of the tubes if it is necessary to remove those adjacent to these supports. In such case, the bolts for one of the pieces 79 are removed 70 with the piece, after which the fittings can be more readily manipulated. Each header is supported by more than one of the pieces 79, so that one piece may be removed without interfering with the header support. If necessary, the headers can be jacked upwardly 75 in order to replace the supporting pieces 79.

The withdrawal of steam and water to a separating tank or vessel, in which the water is separated from the steam, is an important 80 feature. Where a superheater is used, the steam is thus taken in a comparatively dry state to the superheater. The provision of this tank makes it possible to carry a much more uniform degree of superheat and a 85 more uniform pressure than could be obtained without the separating receptacle. The tank also serves a useful purpose where there are impurities in the water, as the steam free, or practically free from the impurities, 90 flows from the separating tank into the superheater, the impurities collecting in the water.

Bleeding the water from the steam and water drum or separating tank is also an 100 important feature, as it permits of a re-circulation of such water through the tubes with or without fresh make-up water. As a consequence the water flowing through the tubes is all pump circulated and its amount is 105 always in excess of what can be evaporated to an extent regulated by the bleeding. This makes it sure that no tube even in the hottest zone can become overheated in normal operation.

The action secured through bleeding out a certain amount of water from the steam and water drum is as follows:

To maintain a given height of feed water in the drum, the feed must be adjusted so that it will correspond to the steam evaporated plus the water drawn out from the drum. If the rate at which the water is fed is too low, the water level will fall, through the water being bled away from the drum, 115 and if too great, the water level will rise, through more water being fed into the drum than is bled away from the drum.

Should no water be bled away from the drum, there would be no variation in the 120 water level in the drum except that caused through over-feeding the boiler, which would result in the water level rising in the drum, and after rising in the drum, the water level would not fall even should too little 125

water be fed to the boiler. The draining off of a regulated amount of water from the steam and water drum is, therefore, a most important feature, as it makes possible the 5 control of the feed water through a regulator which acts through variation in the height of the water in the drum, and also makes possible the feeding of sufficient water to the boiler tubes to have an excess of water going 10 through them over and above that which is vaporized in the tubes, thus obtaining saturated steam at the outlet with the water. The feed-water regulators used in connection with ordinary steam boilers are in the 15 main operated through variation in water level in the boilers, and by providing a series boiler where the feed water can be controlled through the means of a variation in the water level of a separator tank, it is possible to 20 employ standard apparatus for the purpose.

In the foregoing description and the appended claims, I have used the term "feed water" to designate the water fed to the boiler tubes and the term "make-up water" to 25 designate the water added from an outside source to the volume of water from which the feed water is taken.

What I claim and desire to secure by Letters Patent of the United States is:

30 1. In the operation of a series boiler, the steps consisting of withdrawing mingled steam and water from the boiler, separating the water from the steam, maintaining a pool of the separated water, continuously 35 removing a substantially uniform amount of water from the pool, forcing an amount of feed water sufficient to provide for the steam evaporated in the series boiler and for the amount of water removed from the pool into 40 and forwardly through the tubes of the series boiler by power exterior to the boiler, and controlling the feed of water to the boiler by the level of water in said pool.

2. In the operation of a series boiler, the 45 steps consisting of withdrawing mingled steam and water from the boiler, separating the water from the steam, maintaining a pool of the separated water, continuously removing a substantially uniform amount of 50 water from the pool, forcing an amount of feed water sufficient to provide for the steam evaporated in the series boiler and for the amount of water removed from the pool into and forwardly through the tubes of the series 55 boiler by power exterior to the boiler, utilizing variations in the water level in the pool to control the feed of water to the boiler, and utilizing heat in the water removed from the pool to heat the feed water.

60 3. In the operation of a series boiler, the steps consisting of withdrawing mingled steam and water from the boiler, separating the water from the steam, maintaining a pool of the separated water, continuously 65 removing a substantially uniform amount of

water from the pool, forcing an amount of feed water sufficient to provide for the steam evaporated in the series boiler and for the amount of water removed from the pool into and forwardly through the tubes of the series 70 boiler by power exterior to the boiler, utilizing variations in the water level in the pool to control the feed of water to the boiler and returning the water withdrawn from the pool to the boiler.

4. In the operation of a series boiler, the steps consisting of withdrawing mingled steam and water from the boiler, separating the water from the steam, maintaining a pool of the separated water, continuously removing water from the pool, forcing an amount of feed water sufficient to provide for the steam evaporated in the series boiler and for the amount of water removed from the pool into and forwardly through the tubes of the series 80 boiler by power exterior to the boiler, and utilizing heat in the water removed from the pool to heat the feed water.

5. In the operation of a series boiler, the steps consisting of withdrawing mingled steam and water from the boiler, separating the water from the steam, maintaining a pool of the separated water, withdrawing a regulated amount of water from said pool, mingling make-up water with the water withdrawn from the pool and conducting the mingled water to the boiler, and automatically increasing or decreasing the flow of mingled water in response to a respective rise 90 or fall of the water level in the pool.

6. In the operation of a series boiler, the method of forcing water through the boiler at such a rate that only a portion of it is converted into steam, continuously withdrawing the mingled steam and water from the boiler, separating the water from the steam to form a pool, withdrawing water from the pool, mingling make-up water with the water withdrawn from the pool, conducting the mingled water to the boiler and automatically increasing or decreasing the flow of the mingled water to the boiler in response to a respective rise or fall of the water level in 105 the pool.

7. In the operation of a series boiler, the steps consisting of withdrawing mingled steam and water from the boiler, separating the water from the steam, maintaining a pool of the separated water, continuously withdrawing water from the pool, mingling make-up water with the water withdrawn from the pool, conducting the mingled water to the boiler, and automatically controlling the supply of water to the boiler to produce the same amount of water at the exit of the boiler as 115 is withdrawn from the pool.

8. The method of operating a series boiler which consists in causing water to issue from the boiler with the steam, separating the water from the steam to form a pool, with- 120

drawing a regulated amount of water from said pool, mingling make-up water with the water withdrawn from the pool, conducting the mingled water to the boiler, utilizing the water so separated to control the water supplied to the boiler, and withdrawing the steam separated from the water independently of the water level in said pool.

9. The method of operating a series boiler which consists in causing water to issue from the boiler with the steam, separating the water from the steam and forming a pool of water, withdrawing a regulated amount of water from said pool, mingling make-up water with the water withdrawn, conducting the mingled water to the boiler and automatically increasing or decreasing the flow of water to the boiler in response to a respective rise or fall of the water level in said pool.

10. The method of operating a series boiler which consists in causing water to issue from the boiler with the steam, separating the water from the steam and forming a pool of water, withdrawing water from said pool, mingling make-up water with the water withdrawn from said pool, conducting the mingled water to the boiler and automatically increasing or decreasing the flow of mingled water in response to a respective rise or fall of the water in said pool.

11. In a series boiler comprising steam generating tubes, a receptacle, connections for conducting steam and water from the generating tubes to said receptacle, means for continuously removing from said receptacle a substantially uniform amount of water, means for forcing an amount of feed water sufficient to provide for the steam evaporated in the series boiler and for the amount of water removed from the receptacle into and forwardly through the tubes of the series boiler by power exterior to the boiler, and means operable by conditions within the receptacle for controlling the rate of feed of the feed water to the boiler.

12. In a series boiler comprising steam generating tubes, a receptacle, connections for conducting steam and water from the generating tubes to said receptacle, means for continuously removing from said receptacle a substantially uniform amount of water, means for forcing an amount of feed water sufficient to provide for the steam evaporated in the series boiler and for the amount of water removed from the receptacle into and forwardly through the tubes of the series boiler by power exterior to the boiler, means responsive to conditions within the receptacle for controlling the rate of feed of the feed water to the boiler, and means for utilizing the heat in the water removed from the receptacle to heat the feed water.

13. In a series boiler comprising steam generating tubes, a receptacle, connections for

conducting steam and water from the generating tubes to said receptacle, means for continuously removing water from the receptacle, means for forcing an amount of feed water sufficient to provide for the steam evaporated in the series boiler and for the amount of water removed from the receptacle into and forwardly through the tubes of the series boiler by power exterior to the boiler, and means operable by conditions within the receptacle for controlling the rate of feed of the feed water to the boiler.

14. In a series boiler comprising steam generating tubes, a receptacle, connections for conducting steam and water from the generating tubes to said receptacle, means for continuously removing from said receptacle a substantially uniform amount of water, means for forcing an amount of feed water sufficient to provide for the steam evaporated in the series boiler and for the amount of water removed from the receptacle into and forwardly through the tubes of the series boiler by power exterior to the boiler, means responsive to conditions within the receptacle for controlling the rate of feed of the feed water to the boiler, and connections for supplying the water withdrawn from said receptacle to said second-named means.

15. In a series boiler comprising steam generating tubes, a receptacle, connections for conducting steam and water from the generating tubes to said receptacle, means for continuously removing from said receptacle a substantially uniform amount of water, means for forcing an amount of feed water sufficient to provide for the steam evaporated in the series boiler and for the amount of water removed from the receptacle into and forwardly through the tubes of the series boiler by power exterior to the boiler, means responsive to the water level in said receptacle for controlling the rate of feed of water to the boiler, and means for utilizing the heat in the water removed from the receptacle to heat the feed water.

16. In combination, a steam boiler, means for feeding water to said boiler, a steam and water separating tank, connections for carrying the steam and water from said boiler to said tank, means for withdrawing water from said tank, means for mingling make-up water with the water withdrawn from said tank, means for conducting the mingled water to the boiler, means for controlling the water supplied to the boiler in accordance with the water level in said tank, and means independent of the water level in said tank for withdrawing steam therefrom.

17. In combination, a steam boiler, means for feeding water to said boiler, a steam and water separating tank, connections for carrying the steam and water from said boiler to said tank, means for withdrawing water from said tank, means for mingling make-up

water with the water withdrawn from said tank, means for conducting the mingled water to the boiler, a float-operated valve actuated by the water in said tank for controlling the flow of water to the boiler, and means independent of the water level in said tank for withdrawing steam therefrom.

18. A series boiler having a separating tank or vessel, means for maintaining water at a certain level therein including a connection leading steam and water from the boiler to said vessel, means for regulating the feed to the tank in accordance with the water level in said tank, and means for bypassing the vessel in starting the boiler.

19. A series boiler having a separating tank or vessel, means for maintaining water at a certain level therein including a connection leading steam and water from the boiler to said vessel, means for regulating the feed to the tank in accordance with the water level in said tank, means for bypassing the vessel in starting the boiler, and an adjustable steam outlet arranged to blow off steam and water in starting up the boiler.

20. In a series boiler having a closed circuit and comprising steam generating tubes, means for forcing a mixture of steam and water through the generating tubes, a tank, connections for conducting the steam and water from the generating tubes to said tank, the water being separated from the steam in said tank, means for continuously withdrawing from the separating tank a uniform amount of water, means for mingling make-up water with the water withdrawn from said tank, means for conducting the mingled water to the boiler, and means independent of the amount of water in said tank for withdrawing steam therefrom.

21. In a series boiler having a closed circuit and comprising steam generating tubes, means for forcing a mixture of steam and water through the generating tubes, a tank, connections for conducting the steam and water from the generating tubes to said tank, the water being separated from the steam in said tank, means for continuously withdrawing from the separating tank a uniform

amount of water, means for mingling make-up water with the water withdrawn from said tank, means for returning the mingled water to the boiler, means for regulating the amount of mingled water conducted to the boiler in accordance with the water level in said tank, and means independent of the amount of water in said tank for withdrawing steam therefrom.

22. The method of operating a forced circulation series boiler which comprises forcing water thereinto in excess of the amount evaporated, separating the steam and water issuing therefrom, and recirculating the separated water through the boiler along the same path with the incoming make-up water by power exterior to the boiler.

23. The method of operating a forced circulation series boiler which comprises forcing water thereinto in excess of the amount evaporated, separating the mixture of steam and water issuing therefrom, mixing the separated water with make-up water, and forcing the two together into said boiler along the same path by power exterior to the boiler.

24. In the operation of a series boiler, the steps consisting of withdrawing mingled steam and water from the boiler, separating the water from the steam, maintaining a pool of the separated water, continuously removing water from the pool and forcing an amount of make-up water sufficient to provide for the steam evaporated in the series boiler and for the amount of water removed from the pool into and forwardly through the tubes of the series boiler by power exterior to the boiler.

25. In combination, a steam boiler, means for feeding water to said boiler, a steam and water separating tank, connections for carrying the steam and water from said boiler to said tank, means for withdrawing water from said tank, means for mingling make-up water with the water withdrawn from said tank, and a single pump for forcing the mingled water into the boiler.
